G. Kennedy
ATTORNEY

UNITED STATES PATENT OFFICE

JOSEPH M. KYLE, OF GREENE, IOWA

HAYFORK

Application filed October 29, 1930. Serial No. 431,927.

My invention relates to improvements in hayforks, and the object of my improvement is to supply an improved device of this class, of simple construction, and more effective in use than two-pronged forks for taking on, transporting and delivering portions of hay or the like.

This object I have accomplished in actual practice by the means which are hereinafter described and claimed, and which are illustrated in the accompanying drawings, in which Fig. 1 is an elevation of my improved multi-pronged hayfork, with its engaging detents set in extended position as in securing thereto a portion of a load, and Fig. 2 is an under plan of the same.

The numeral 1 denotes a tubular stem, but which may be of less diameter and solid if desired, and 2 denotes a plurality of radiating arms fixed on and projecting horizontally from the upper part of the stem 1, each arm preferably shaped in a narrowly looped form with side bars in parallel first extending outwardly and then bent downwardly vertically to be united at an acute angle at their lower terminations 20, said side bars being equally spaced apart throughout. As shown, the arms are arranged about the stem 1 in a cruciform shape and of equal length in their radiating parts, but less or more arms may be employed as desired, or suitable for the work to be performed, and certain of the arms in their radiating parts may be shorter than other arms, or when the cruciform arrangement is employed, one pair of arms intermediate the others may be of less length than such other arms, without departing from this invention.

A fitting sleeve 7 is mounted slidably on the stem 1, and has short radial lugs 9 thereon apertured to receive the pintles 10 on which are pivoted at their inner ends the flat bar links 11. The numeral 13 denotes short bell-crank levers pivoted at their outer ends between the bars of said arms 2 on pintles 14. The inner ends of the levers 13 are pivotally connected to the outer ends of the links 11 by pintles 12. The numeral 16 denotes longer depending link bars whose upper ends are

pivoted to medial parts of the levers 13 on pintles 15.

The numeral 18 denotes detents pivoted near their inner or upper ends on pintles 19 and between the side bars of the arms 2 immediately above the pointed terminations 20 of the arms, but with sufficient spaces provided to receive the outer and longer parts of the detents when retracted therebetween. The lower ends of the depending links 16 are pivoted to the shorter inner parts of the detents 18 on pintles 17.

An upwardly directed curvate loop 5 is fixed at the upper end of the stem 1 or a part of the adjacent arm 2 thereon at one side and is traversed by a cable 6 passed downwardly through it to and fastened terminally to a like eye or loop 8 at one side and directly below on the sleeves 7.

At the top of the stem 1 may be fixed a cross member 3 with a medial eye to receive one end of another cable 4 fastened thereto. This cable may be reeved about a sheave not shown, or other device, for lifting the fork and transporting it to a place of deposit for its load.

When the fork has its detents first retracted between its arm bars by manually moving the sleeve 7 upwardly, which acts upon said connections 11, 13 and 16 to the detents to swing them between said arm bars, the fork may be lowered to have its prongs or arms 2 penetrate a quantity of hay or other similar material. Then the sleeve may be pressed downwardly to cause its connections to said detents to extend them as shown in Fig. 1, whereby the detents enter the load and retain it on the fork until a place of deposit is reached, when the cable 6 may be pulled to cause the detents to be retracted, thus discharging the load easily from the prongs 2.

The sleeve 7 equalizes the action on all of the detents, and is strongly centered upon the stem 1, whereby a balance is obtained in use, and the moving elements reinforced.

The plurality of arms, especially the cruciform arrangement shown, aid in holding in the load all around and preventing escape of parts thereof from the sides or the medial intervals of the arms.

Having described my invention, what I

claim as new, and desire to secure by Letters Patent, is:

1. A central stem having radiating angular arms whose farther parts are directed downwardly in spaced relation, a sleeve slidably mounted on said stem below the inner parts of said arms, detents pivoted on the lower terminations of said arms to swing from positions parallel thereto to positions outwardly angularly relative thereto, and operating connections linkedly connected between said sleeve, said arms, and said detents.
2. A central stem having radiating angular arms extending from the upper part of said stem in cruciform shape and with their farther parts bent downwardly in parallel relation to the stem, a sleeve mounted slidably on said stem below the radiating parts of said arms, detents pivoted on the lower terminations of said arms to swing from positions parallel thereto to positions angularly outwardly therefrom, and operating connections linkedly connected between said sleeve, said arms and said detents.
3. A central stem having radiating angular arms extending from the upper part of the stem and with their farther parts bent downwardly in parallel relation to the stem, a slidable sleeve on said stem, each arm being composed of parallel bars united at their lower terminations with a wedge-shape, detents pivoted between the lower parts of said arms to swing to and from positions parallel thereto to positions angularly outwardly therefrom, and operating connections linkedly connected between said sleeve, said arms and said detents.
4. A central tubular stem having projecting arms at its upper end bent downwardly in transversely spaced relation, each arm being composed of spaced parallel bars united at their lower ends, a sleeve mounted slidably on said stem below the projecting parts of said arms, detents pivoted between the lower parts of said arms to swing to and from outwardly therefrom, bell-crank levers pivoted between the upper parts of said arms, links connected respectively between said levers, said sleeve and said detents, and means for shifting said sleeve on said stem in one direction.

In testimony whereof I affix my signature.
JOSEPH M. KYLE.
